SANITARY EYESHADE

Roy C. Seeley, Los Angeles, Calif.

Application September 25, 1939, Serial No. 296,405

2 Claims. (Cl. 2-12)

The present invention pertains to an improved light weight, readily manufactured, unitary eyeshade or device adapted to be worn over the eyes for the purpose of preventing light from disturbing the rest or sleep of the wearer.

Eyeshades have been used by numerous individuals suffering from insomnia or particularly sensitive to light or illumination. Many persons can not rest or sleep unless they are in substantially total darkness and for that reason do not relax and rest during daylight hours even though their occupation or circumstances make it desirable that they sleep. Prior devices used for similar purposes have been expensive, bulky and in many instances uncomfortable to wear. Furthermore, repeated use of prior devices causes the same to absorb perspiration and body oils which render the devices disagreeable, soiled and unpleasant.

The present invention is primarily directed toward a very effective but simplified form of eyeshade which, by reason of its simplicity and inexpensive character, may be discarded after use, thereby permitting the wearer to use a clean and unsoiled eyeshade without excessive expenditures. Furthermore, certain of the forms of eyeshade hereinafter disclosed not only protect the eyes of the wearer from disturbing light but also include means whereby the wearer may effectively prevent extraneous noises from disturbing his rest.

An object of the present invention, therefore, is to provide a simple, inexpensive, light weight eyeshade.

Another object of the present invention is to disclose and provide a unitary self-adjusting, light weight eyeshade.

A further object of the present invention is to disclose and provide an eyeshade provided with means for protecting the eyes from extraneous light and simultaneously protecting the wearer from disturbance due to extraneous noise.

Other uses, advantages, adaptations and modifications of the invention will become apparent to those skilled in the art from the following detailed description and from the drawing appended hereto, which drawing shows a number of modifications and illustrative forms.

In the drawing:

Fig. 1 is an elevation of one form of eyeshade of this invention.

Fig. 2 illustrates the manner in which the device may be used.

Figs. 3, 4, 5 and 6 illustrate modified forms of the device.

The eyeshades of the present invention may be made of any suitable light weight, virtually opaque, fibrous or felted material such as, for example, paper preferably uncalendered and soft and flexible. The device itself may be made out of a number of laminations of very light weight porous and absorbent webs, films or tissues of fibrous material suitably pressed, felted or cemented together, or the device may be made of a unitary web of material of slightly heavier gage than the individual sheets of a laminated form. Those skilled in the art of paper manufacture will readily appreciate the variety of types of paper which may be employed, it being remembered that the device should be practically opaque and still relatively soft and flexible so as not to include sharp edges or folds which might cause discomfort to the wearer.

As shown in Fig. 1, the device, generally indicated at 10, may comprise a piece of fibrous material having the end portions 11 and 12, the device 10 being of sufficient length to extend from ear to ear and across the eyes of a wearer. If desired, the body portion 13 of the device is of a width sufficient to extend from the eyebrows of a wearer to the cheek of the wearer and such width may vary from about 2½ inches to 3½ inches although these measurements are exemplary only. Moreover, the end portions 11 and 12 may be displaced from the longitudinal axis of the body portion 13, the end portions 11 and 12 in Fig. 1 being shown displaced downwardly from the longitudinal axis of the body portion 13. The end portions 11 and 12 are preferably formed as an integral part of the body portion 13 and are connected to such body portion by means of sections of a reduced width, such reduction in width being indicated at between the points 14 and 15.

Each of the end portions 11 and 12 may have a slit or cut made therein, each of such slits or cuts being arcuate in form as indicated at 17 and forming an approximately triangular or C-shaped opening in the ends, thus liberating a tab-like member 18 attached to the constricted portion of the body 13. The fibrous material between the slit 17 and the outer edge of the end 11 forms a loop 19 adapted to be placed around the ear of the wearer, the tab 18 overlying the opening to the ear when the device is in position. This tab 18 may be permitted to overlie this opening or it may be crumpled and inserted into the opening of the ear as more particularly shown in Fig. 2, which illustrates the manner in which the device may be used.

By referring to Fig. 2 it will be seen that the body portion 13 of the device covers the eyes of the wearer and because of its flexibility, conforms to the contours of the features, excluding extraneous light from impinging upon the eyes. The ear 20 of the wearer extends through the C-shaped opening formed by the slit 17, the loop 19 now holding the device in position on the head of the wearer. The tab-like member 18 has been crumpled and pressed lightly into the opening of the ear as indicated at 18'. It is to be understood that the opposing end 12 of the device has been similarly placed over the other ear of the wearer. When used in the manner described, the wearer is protected not only from noise but the wearer may rest without disturbance from light, such as excessive daylight or the light of flashing signs. It is to be further noted that the crumpled tabs 18 assist in holding the device in position.

Fig. 3 shows a slightly modified form of device in which the body portion 13 is provided with a slit 21 extending from lower edge thereof upwardly and inwardly, such slit being adapted to accommodate the nose of the wearer, thereby permitting the body portion 13 to more closely contact with the ears and on either side of the nose and thereby more positively excluding light from the eyes. It is also to be noted that in the form of device shown in Fig. 3, the constricted portions, generally indicated at 22 and 23, have been crinkled so that the end portions 11 and 12 of the device may be grasped and the overall length of the device increased, when desired, the crinkled portions 22 and 23 permitting a certain amount of expansion to take place, which, of course, aids the device in conforming to the features, and thus aids it in its function of excluding light. When this feature is incorporated in the device, it is preferable that the strip be constructed of slightly shorter length than the distance between the points of attachment to the wearer's ears, thus necessitating that the strip be tensioned slightly when it is placed in operative position, with the result that the security of its mounting upon the person's features is enhanced.

The device shown in Fig. 4 distinguishes from those previously described in that the body portion 13 includes an upwardly directed slot having the edges 24 and 25, the slot or opening thus formed being adapted to accommodate the nose of the wearer, said body portion terminating in integral hook-like ends 26 and 27 adapted to fit around the ears of the wearer. If desired, a narrow constricted portion connecting the hook-like ends to the body 13 may, as shown at 22' and 23', be crinkled or gathered during the formation of the device so that the overall length of the device may be increased by expanding the crinkled areas 22' and 23'. The ends of the device may be of increased thickness to give greater strength to the hook-like ends.

A very simple modification of the present invention is indicated in Fig. 5. The device there shown includes a body portion 13 having taper-

ing end sections 28 and 29, these tapering end sections terminating in enlargements 30 and 31. These enlargements 30 and 31 may be crumpled to form a ball or plug adapted to be inserted into the ears of the wearer. Obviously, whenever so desired the tapering sections 28 and 29 may be provided with wrinkles, corrugations or other deformations from the plane of the material so as to permit lengthening if this is deemed desirable. Moreover, the body portion 13 may be provided with a slit such as 21 (Fig. 3) or an indentation adapted to receive the nose. Instead of a slit, the body portion may be crinkled in the middle to permit stretching over the nose. A still further modification is illustrated in Fig. 6. As there shown, the body portion 13 is provided with downwardly directed ends 32 and 33. The lower portion of the body may be provided with an indentation 34. The portions 32 and 33 may comprise flaps adapted to cover the ears or such ends may be crumpled up and inserted into the ears. In order to facilitate retention of the device on the wearer, a solution of gum arabic, gum tragacanth or other vegetable gum or material having some adhesive properties may be applied to the inner surface of the device at portions normally covering the temples as, for example, at 35 and 36. These portions, when pressed against the skin of the wearer, cause the device to lightly adhere thereto.

As indicated hereinabove, all of the eye-shades of the present invention may be cut out of a sheet of fibrous material such as paper of a suitable weight, texture and flexibility. Such paper may be suitably colored, if desired. More elaborate forms of the eye-shade of this invention may be produced from a woven or knitted fabric.

Although specific forms of the invention have been described in detail, it is to be understood that the various forms may be combined or elements shown embodied in one form may be also embodied in other forms.

All changes and modifications coming within the scope of the appended claims are embraced thereby.

I claim:

1. An eyeshade comprising a unitary piece of flexible, pliant, substantially opaque material of a length sufficient to extend from ear to ear and across the eyes of a wearer, the ends of said piece being formed with integral means to attach the shade to the ears, said integral attaching means including a flap adapted to be crumpled and inserted into the opening of the ear to retain said eyeshade in operative position.

2. An eyeshade comprising a unitary piece of flexible, pliant, substantially opaque material of a length sufficient to extend from ear to ear and across the eyes of a wearer, the ends of said piece being formed with integral means to attach the shade to the ears, said material being crinkled in portions of said piece whereby said shade may be lengthened by stretching.

ROY C. SEELEY.
